UNITED STATES PATENT OFFICE.

GREENE CARLTON HOSCH, OF ST. LOUIS, MISSOURI, ASSIGNOR TO THE MEASURE-
GRAPH COMPANY, OF ST. LOUIS, MISSOURI, A CORPORATION.

MEASURING-ROLLER.

1,390,956.

Specification of Letters Patent. Patented Sept. 13, 1921.

Application filed June 28, 1919. Serial No. 307,345.

To all whom it may concern:

Be it known that I, GREENE CARLTON HOSCH, a citizen of the United States, residing in the city of St. Louis and State of 5 Missouri, have invented new and useful Improvements in Measuring-Rollers, of which the following is a specification.

This invention relates to fabric measuring and cost computing machines, and particularly to the type of such machines which employ a measuring roller having a special coating or clothing for its face. The surface of this covering must develop a certain amount of friction to insure that there will 10 be no slip of the measured fabric on the surface of the roller when the fabric is being drawn through the measuring machine.

The composition most suitable for this covering or clothing of such a roller, is a mixture of carborundum dust and sodium silicate, but the friction-developing property of this composition has a certain disadvantage in the practical operation of the machine which arises in introducing the 15 edge of the fabric into the measuring gap.

The object of this invention is to overcome this disadvantage, and to produce a roller of special form which will facilitate the application of the shell to it, and, which, 20 at the same time, will overcome the disadvantage inherent in such a roller.

The invention consists in the novel features of parts to be particularly described hereinafter, all of which contribute to produce a simple and efficient measuring roller 25 for a fabric measuring and cost computing machine. A preferred embodiment of my invention will be particularly described in the following specification, while the broad 30 scope of my invention will be pointed out in the appended claims.

In the drawing, which fully illustrates my invention,

Figure 1 is a vertical section taken 35 through the lower portion of a measuring machine of the type referred to, illustrating the measuring roller in longitudinal section;

Fig. 2 is a vertical section taken about on 40 the line 2-2 of Fig. 1;

Fig. 3 is a plan illustrating apparatus by means of which the roller may be provided with its clothing or covering; and

Fig. 4 is a vertical section taken on the 45 line 4-4 of Fig. 3, and particularly illus-

trating how the form of the roller may co-operate to facilitate the application of the clothing or shell to the core of the roller.

Referring more particularly to the parts, the measuring roller comprises a metallic 50 core 1 which may be formed of aluminum, said core having a transverse head 2, the inner face of which is provided with a counter-bore 3 to form a bearing for the core, seating on the end of an arbor 4 which is fixed in a vertical wall 5 of the frame of the machine. This arbor is of tubular form and carries a shaft 6 for driving indicating mechanism, (not illustrated), the outer end of the shaft being rigidly secured in a hub 70 7 formed on the head 2 of the core 1. The cylindrical surface of this core is provided with a covering or clothing in the form of a shell 8, which is in the present instance, formed of a suitable composition, such as 75 sodium silicate and emery and the outer end of the core 2 is provided with an outwardly projecting flange 9 which covers the end of this shell 8.

A presser roller co-operates with the measuring roller by pressing the fabric against it when the fabric is being measured.

The flange 9 performs a double function, the first of which arises from the fact that it operates as a stop for the shell in being placed 85 on the core. One manner in which this flange may perform this function will be described, when the composition shell is molded directly onto the roller.

Referring particularly to Figs. 3 and 4, 10 represents the base plate of a mold, which also includes two co-operating sections 11 and 12 which come together on vertical faces 13 provided with dowel pins 14, and co-operating sockets 15 carried on the opposite 95 mold section. The core 1 of the roller is set up on a vertical axis in the center of this mold with the flange 9 seated on the bottom of the mold. The internal diameter of the mold is very slightly greater than the diameter of this flange 9.

Before pouring the composition into the mold, the inner face of the mold is provided with a tubular liner 16 of paper. The upper end of the core 1 is then provided with a cap 17 which forms a covering for the end of the core and prevents the composition from passing into the interior of the core when the composition is being poured. The composition, which is preferable for forming 110

this shell, is any of the well known mixtures of carborundum dust and sodium silicate. This composition 18 is poured from a ladle 19 into the mold, the lower part of the shell 5 8 resting upon the flange 9 which forms a stop for the shell. The composition should be tamped and permitted to set.

If desired, the cylindrical face of the core 1 may be provided with longitudinal corrugations 20 which produce an interlocking contact between the inner surface of the shell and the outer surface of the core, effectively preventing any relative rotary movement of the shell and core.

15 It should be understood that these measuring machines are often used for measuring delicate silks and fine ribbons, and if a roller having a covering suitable for developing sufficient friction is employed, having an exposed end, the exposed end is more or less rough, and tends to injure the edge of such fine material when being dragged over the end of the roller in guiding the material into the measuring gap between the measuring roller and the presser roller. In Fig. 1 20 the outline of the presser roller is indicated at 21 which shows approximately the position of the presser roller when separated from the measuring roller to permit the introduction of the material to be measured. As this gap is not wide, it is customary for the operator, in inserting the fabric, to hold the extreme edge of the ribbon or cloth against the end of the roller, then elevate the 25 edge into the gap, and then drag the material over the end of the roller, further into the gap.

When the roller is constructed in accordance with this invention, the polished metal

surface of the flange quickly guides the edge 40 of the material into the gap and no injury can be done to the surface of the material by drawing it over the edge of the flange in pulling the material well into the gap. In practice, the outer surface of the shell is 45 turned accurately to the desired pre-determined diameter. The outer diameter of the flange 9 should be about 1-100 of an inch smaller than the diameter over the shell.

What I claim and desire to secure by Letters Patent is:

1. In a cloth measuring machine, a measuring roller consisting of a metallic core with a molded shell of composition on the cylindrical face thereof, said shell having a rough outer face, said core having a flange at one end only operating as a stop to limit the movement of the composition shell when being placed on the core of the roller, and covering the end of the shell to prevent the edge of the cloth engaging the same when being passed into the machine and along the surface of said roller.

2. In a cloth measuring machine, a measuring roller, consisting of a metallic core 65 with a shell on the cylindrical face thereof, said shell having a rough outer face, said core having a flange at one end only operating as a stop to limit the movement of the shell when being placed on the core of the roller, and covering the end of the shell to prevent the edge of the cloth engaging the same when being passed into the machine and along the surface of said roller.

In testimony whereof, I have hereunto set my hand.

GREENE CARLTON HOSCH.
